ATTORNEY

UNITED STATES PATENT OFFICE.

JONATHAN PERKINS, JR., OF SAN DIEGO, CALIFORNIA.

BIT-HOLDER EXTENSION.

1,405,625.

Specification of Letters Patent. Patented Feb. 7, 1922.

Application filed March 11, 1920. Serial No. 364,892.

To all whom it may concern:

Be it known that I, JONATHAN PERKINS, Jr., a citizen of the United States, residing at San Diego, in the county of San Diego and State of California, have invented a certain new and useful Bit-Holder Extension, of which the following is a specification.

My invention relates to an extension member for holding bits and the like and the objects of my invention are: First, to provide a bit holder extension which is so constructed that it is of a minimum diameter so that it will enter the hole behind the bit when the bit is of small diameter; second, to provide a bit holder extension of this class in which the bit will be held securely and will not loosen; third, to provide a device of this class in which the means for holding the bit engaging members is supported by a nut at the opposite end, forming a part of the extension shank; fourth, to provide a device of this class in which the bit is readily secured and may be readily removed, and fifth, to provide a device of this class which is simple and economical of construction, durable, easy to operate, efficient in its action and which will not readily deteriorate or get out of order.

With these and other objects in view as will appear hereinafter, my invention consists of certain novel features of construction, combination and arrangement of parts and portions as will be hereinafter described in detail and particularly set forth in the appended claim, reference being had to the accompanying drawings and to the characters of reference thereon which form a part of this application, in which:

Figure 1 is a longitudinal sectional view of the device, showing a portion of the clamp members and bit stock in elevation; Fig. 2 is a side elevational view at a right angle to that of Fig. 1 minus the bit stock; Fig. 3 is a sectional view through 3-3 of Fig. 1; Fig. 4 is a sectional view through 4-4 of Fig. 1; Fig. 5 is a sectional view through 5-5 of Fig. 1 and Fig. 6 is a sectional view through 6-6 of Fig. 1.

Similar characters of reference refer to similar parts and portions throughout the several views of the drawings.

The main hollow member 1, rod 2, nut 3, clamping members 4 and 5 pin 6, spring 7 and spring 8 constitute the principal parts and portions of my bit holder extension.

The main hollow member 1 is provided with a longitudinal hole 1^a, in which the rod 2 is adapted to fit and provided with sufficient clearance to permit its ready removal. It is provided on one end with a shank portion 1^b, which is of the conventional form, except that it is approximately one-half the usual length, the other one-half being supplied by means of a nut 3, which conforms to the portion 1^b and provides a gradual taper. This nut 3 is internally threaded adapted for the thread 2^a on the end of the rod 2. On the opposite end of the main hollow member 1 is provided an enlarged portion 1^c which is also provided with an enlarged internal recess 1^d, in which is mounted a compression spring 7, which rests against the shoulders 1^e at its one end and pivotally mounted on the opposite end of this rod 2 are the clamp members 4 and 5, by means of a pin 6 extending through a hole in the end of the member 2 and the opposite end of the spring 7 rests against the ends of the clamp members 4, thus tending to hold the clamp members outwardly at all times so that when the nut 3 is released the spring 7 tends to thrust the clamp members out of the end of the portion 1^c. This portion 1^c is provided with oppositely disposed diverging walled slots 1^f, which conform to angles on the outer surface of the clamp members 4, so that when the clamp members are drawn into the member by means of the nut 3 on the end of the rod 2 the outer ends of the clamp members 4 are pressed toward each other engaging the shank of the bit. It will be noted that these clamp members are so shaped that they engage the corners of the bit as shown best in Figs. 4 and 5 but are shaped to conform to the round portion of the bit shank near the outer ends as shown best in Fig. 3 of the drawings. Mounted between the shank members is a compression spring 8, tending to hold them apart so that when said shank members are moved outwardly this spring 8 gradually spreads the shank members apart so that they are ready to release the bit shank and receive another one.

Though I have shown and described a particular construction, combination and arrangement of parts and portions I do not wish to be limited to this particular construction, combination and arrangement but desire to include in the purview of my in-

vention the construction, combination and arrangement substantially as set forth in the appended claim.

It is obvious that with this construction 5 there is provided a bit holder extension in which the shank of the bit is clamped between two clamping members by being pressed into the inclined surface slots in the one end of the main supporting member. 10 That the clamping members are mounted in slots so that they can not turn and the nut on the end of the rod is positioned in the end of the bit driver so that it can not turn so that the bit can not loosen nor any of the 15 parts move so that the bit will loosen while operating, that the construction is such that the larger part of the extension may be made of small diameter so that said extension may be used in a small hole following 20 the bit.

Having thus described my invention what

I claim as new and desire to secure by Letters Patent, is:

A bit holder extension, including a main hollow supporting member, provided with a 25 tapering square exterior at one end, a rod extending longitudinally therein, a nut screwed onto the one end of said rod provided with a tapering square exterior forming a continuation of said tapering square 30 supporting member, and both forming a conventional tapered square shank for the conventional bit driver, a pair of oppositely disposed clamping members engaging inclined inner surfaces of said main bit member, whereby they are clamped together when moved inwardly.

In testimony whereof, I have hereunto set my hand at San Diego, California this 2nd day of March, 1920.

JONATHAN PERKINS, JR.
